(57) **CLAIM**

The ornamental design for a security camera pedestal mount, as shown and described.

DESCRIPTION

FIG. 1 shows a front perspective view of the security camera pedestal mount showing our new design;

FIG. 2 shows a left perspective view of the security camera pedestal mount showing our new design;

FIG. 3 shows a front elevation view of the security camera pedestal mount showing our new design;

FIG. 4 shows a right side elevation view of the security camera pedestal mount showing our new design;

FIG. 5 shows a rear elevation view of the security camera pedestal mount showing our new design;

FIG. 6 shows a top view of the security camera pedestal mount showing our new design; and,

FIG. 7 shows a bottom view of the security camera pedestal mount showing our new design.

The broken line showing portions of a pedestal mount for security camera is included for illustrating environmental structure and forms no part of the claimed design.
